William W. Varney ATTORNEY

UNITED STATES PATENT OFFICE.

CHARLES G. HILL, OF BALTIMORE COUNTY, MARYLAND.

RAZOR-BLOTTER.

1,284,676.

Specification of Letters Patent. Patented Nov. 12, 1918.

Application filed April 14, 1917. Serial No. 161,961.

To all whom it may concern:

Be it known that I, CHARLES G. HILL, a citizen of the United States, residing in the county of Baltimore, in the State of Maryland, have invented a certain new and useful 5 Razor-Blotter, of which the following is a specification.

My invention relates to an improved razor blotter and has for its object the providing 10 of a razor blotter to clean a razor by blotting, thus prolonging its period of usefulness.

A further object of my invention is the providing of a razor blotter to clean both 15 sides of a razor blade simultaneously.

A further object of my invention is the providing of a new article of manufacture comprising a blotting surface provided with a support tending to maintain a definite 20 formed shape.

A further object of my improvement is the providing of a shaped blotter for drying razors or razor blades comprising a blotting surface integral with a supporting surface and provided with means of normally maintaining the two adjacent surfaces in 25 juxtaposition normally separated.

With the foregoing and other objects in view my invention consists of the novel construction, combination and arrangement of parts as hereinafter specifically described and illustrated in the accompanying drawing, wherein is shown the preferred embodiment 30 of my invention, but it is to be understood that changes, variations and modifications can be resorted to which come within the scope of the claim hereunto appended.

In the drawing of the herein described embodiment of my invention:

40 Figure 1, shows the simplest form of my

improvement in the finished shape ready for use. Fig. 2, is a plan view of the blotter shown in Fig. 1, before forming into shape. Fig. 3, is a modified form of a blotter formed into shape ready for use, and Fig. 4 is a section taken through A. B. of Fig. 3. 45

Similar numerals refer to similar parts throughout the several views.

1 is the blotter surface. 2 is the support. The blotter surface and support may be a 50 sleeve or sheath into which spring 3 may be inserted. 3 is the spring or stiffener, which in Fig. 1 is placed within the blotter and support, and bent into shape. 4 is means for hanging the blotter up when in use and 55 may consist of a string or other suitable appliance.

Stiffening member or spring 3 may consist of metal or a sized non-metallic substance. Blotting surface 1 may be made of blotting 60 paper or other absorbent material.

In use the razor blade is inserted between the blotting surfaces, and pressure is applied to the supports with the thumb and finger thus bringing the blotting surfaces together 65 upon the blade.

Having thus described my invention what I claim and desire to secure by Letters Patent is—

An improved blotter consisting of a sheath 70 of material having a blotting surface and a strip of stiffening material inclosed within, said blotter folded upon itself for blotting purposes thus having within itself means tending to maintain said blotting surfaces 75 in a formed position.

CHARLES G. HILL.
